UNITED STATES PATENT OFFICE.

MARVIN MEAD, OF PUEBLO, COLORADO.

HAY-STACKER.

No. 800,383.

Specification of Letters Patent.

Patented Sept. 26, 1905.

Application filed December 8, 1904. Serial No. 236,035.

To all whom it may concern:

Be it known that I, MARVIN MEAD, a citizen of the United States, residing at Pueblo, in the county of Pueblo and the State of Colorado, have invented a new and useful Improvement 5 in Hay-Stackers, of which the following is a specification.

This invention relates to hay stackers and loaders to be used in the field, where hay is delivered to it by means of a bull-rake or similar device.

The object of the device is a stacker adapted for use at the end of a stack delivering the hay in the center with the greatest length of 15 the load delivered transverse to the longitudinal line of the stack.

A further object of the invention is to provide a stacker that will convey the hay from the ground and drop it at any desired point 20 along the longitudinal center of the stack and transverse to said axial line, so that only a small portion of the hay will be required to be moved by hand after having been dumped.

A still further object is a stacker which will commence delivering hay from a comparatively low point and which can be elevated as the stack is built up, thus avoiding the expenditure of time and labor in carrying the hay to a greater height than is absolutely necessary. 25

My invention also consists in the novel features of construction and combination of parts hereinafter described, pointed out in the claims, and shown in the accompanying drawings, in which—

Figure 1 is a side elevation, the carriage being shown in full lines in position to be loaded and in ascending and dumping positions in dotted lines. Fig. 2 is a detail view of the carriage, parts being in section. Fig. 3 is a plan view of the track. Fig. 4 is a plan view, enlarged, of the carriage.

In constructing my stacker I employ suitable base or bed rails A, upon which rest triangular frames A'. These frames and rails are parallel to each other, and in Fig. 1 but one rail and frame are shown. I further provide a movable truss track-section B, which is provided with pivoted supporting-legs C. 45 At their lower ends the legs C carry guide-brackets D, which slide on one member of the frames A' and are provided with a roller D', traveling on its respective frame, as most clearly shown in Fig. 1. These legs C support the track-section B in an inclined position, and the degree of inclination can be va-

ried by means of a cable E, wound upon a suitable drum provided with a ratchet E' and pawl E''. A cable is secured to each of the legs and may run to separate drums independently operated by crank-handles E', or both cables may extend to one drum, so that both can be wound or unwound from one side of the frame by turning the handle E''. In practice I place ratchets E' and handles E'' on each side of the device, so that two men can engage in the work of shifting the inclination of the track. It will be obvious that as the cables E are wound upon the drum or drums the supporting-legs C will be drawn up the incline of the frames A' and the delivering end of the track B elevated.

The track-section B comprises rails B' and cross-ties B''. The ties B'', with the exception of the uppermost one and the lowest, carry brackets B³, in which slide longitudinally with respect to the ties angled rods B⁴. The angled portion B⁵ of these rods curves over one side and under the ties B'', so that they can be reached from below the track by the hand or the tines of a pitchfork in order to shift the position of the rods, sliding them to and away from the rails. On the uppermost tie B'' are arranged adjacent the rails B' bails or staples B⁶, which serve the same purpose as the rods B⁴, but which are not adjustable. The object of the rods B⁴ and bails B⁶, as will more fully appear hereinafter, is to trip the movable carriage and dump the load. 75

The carriage F comprises two racks in the form of rakes, F' and F'', the tines forming the rack F' being longer than those forming the rack F'', the former supporting the hay and the latter serving as a back to hold the load in place. The carriage is provided with wheels G, and I prefer to flange the track-rails B', though smooth rails and flanged wheels could be employed, if desired. The wheels are mounted on short stub-axles H and turn loosely on the same, the carriage F being 100 practically pivoted between the wheels G. Bifurcated brackets H' extend forwardly from each axle H and at their forward ends have an angled catch H'', which is engaged by a 105 slideable hook member J, one of which is arranged on each side of the carriage. The free ends of the brackets H' are connected to cables K, which when taut hold the brackets parallel to the track-rails B', and when the hook member J is in engagement with the catch H'' the carriage F is prevented from turning upon its pivotal points. A spring J', arranged ad-

ja⁵cent each hook member J, normally holds the hook in engagement with the catch H². The lower end of the hook member J is curved downwardly, but will pass freely over the ties B².

The rods B⁴, heretofore mentioned, when moved toward the rails B' will lie in the path of the lower curved ends of the hook members J, which curved portions J² will engage 10 the rods and check the forward movement of the carriage, and the hook will also be withdrawn from engagement with the catch H² on each side of the carriage, and the load will be dumped automatically by reason of its weight, 15 the carriage swinging back into its normal position when relieved of its load.

In order to move the carriage up the inclined track, pulleys L, L', and L² are suitably arranged on the track-section in pairs, 20 one of each pair on a side, and cables K are connected to the free ends of the brackets H' of the rack F and carried over the said pulleys. Any suitable power and form of device, such as a drum rotated by hand or horse power, 25 may be employed to apply the pull on the cables K necessary to draw the carriage up the track.

In operating the device the stacker is placed at the end of the stack and the delivery or forward end of the track elevated to the desired 30 height. The carriage F rests at the lower end of the track, the rack F' being in a horizontal position and upon the ground. The load is delivered upon the rack F², and on applying 35 power to the cables K the first movement of the carriage will be upon its pivotal points, the rack F' lifting the free ends of its tines into a position at an angle to the track B. This movement is of importance, as otherwise 40 in case of bodily movement of the carriage up the track at the first pull on the cables the rack F' would be drawn from under its load and much of the hay would slip from the track. When the carriage has assumed the 45 first position, (shown in dotted lines in Fig. 1,) it moves up the rack until tripped by the portions J² of the hook members J coming in contact with the rods B⁴ or, if the load is to be dumped from the end of the track, with 50 the staples B⁶. The ties B² are spaced sufficiently far apart to permit the load to be dumped between any two of them, and as the stack rises in height the track can be elevated by means of the handles E³ and cables E, as 55 previously stated. The stacker being set at the end of the stack to be formed, the track extends over the longitudinal center or axial line of the stack, and hay can be deposited

upon the stack throughout its entire length by adjusting the various tripping-rods B⁴. 60 When the stack is to be topped, the carriage is tripped by the bails or staples B⁶, and instead of dumping its load the rack F² will rest upon the stack, and the hay can be spread therefrom by forks upon the top, employing 65 the last load to cap the stack.

To those familiar with the stacking of hay, straw, &c., the advantages arising from being able to deposit the load along the longitudinal line of the stack and also of conveying it 70 to the highest point of travel of the carriage before tripping, when desired, will be obvious.

Having thus fully described my invention, what I claim as new, and desire to secure by 75 Letters Patent, is—

1. A hay-stacker comprising an inclined track, adjustable tripper-rods carried by the track, a carriage movable on the track, and mechanism carried by the carriage and adapted 80 to trip the same when in engagement with the rods.

2. A hay-stacker comprising an inclined track comprising rails and cross-ties, a wheeled carriage adapted to travel on the rails, tripper-rods carried by the ties and adjustable with respect to the rails, locking mechanism carried by the carriage adapted to be unlocked by engagement with the tripper-rods, and means for varying the inclination of the 90 track-section.

3. A hay-stacker comprising an adjustable track-section, a carriage comprising pivotally-mounted hay-racks, means for moving the carriage on the track, means for locking the 95 racks against dumping, tripper-rods carried by the track-section, said rods being adjustable and adapted to unlock the racks when engaged by the locking mechanism, and bails carried by the delivery end of the track-section adapted to trip the said carriage.

4. A hay-stacker comprising a track-section, a wheeled carriage adapted to travel on the track and comprising racks arranged at an angle to each other and pivotally mounted 105 between the said wheels, means carried by the carriage for normally locking the racks against rotation on their pivot-points, and adjustable tripper-rods carried by the track-section adapted to unlock the said racks and permit dumping of a load.

MARVIN MEAD.
